UNITED STATES PATENT OFFICE.

ERNEST THOMAS GARLICK, OF SAGINAW, MICHIGAN.

ADVERTISING NOVELTY.

Application filed October 13, 1922. Serial No. 594,297.

To all whom it may concern:

Be it known that I, ERNEST THOMAS GARLICK, a citizen of the United States, residing at Saginaw, in the county of Saginaw and State of Michigan, have invented new and useful Improvements in Advertising Novelties, of which the following is a specification.

My present invention has reference to an advertising novelty.

An object is to produce an advertising novelty in which a figure representing a magician stands before a table and has his hat placed on the table to cover an opening therein, while below the table there is a revoluble wheel comprising a plurality of segments in the nature of shelves, each of said shelves having supported thereon an article, while means is provided for slowly and intermittently rotating the wheel as well as for projecting the shelves on segments thereof through the opening to bring the objects on the shelves or segments above the top of the table, and immediately thereafter means is provided for elevating the hat of the figure, and thereafter lowering the same to again cover the opening in the table when the shelf is lowered and the wheel again revolved, the result being that separate and distinct articles are brought successively to view upon the raising of the hat of the figure so that a novel, amusing and somewhat mystifying result is produced.

A further object is to produce a device of this character which can successfully be employed either as an advertising novelty, or as an amusing toy, and which embodies in its construction the desirable features of simplicity, cheapness in manufacture, and accuracy in operation.

The invention is capable of many embodiments, but only one is herein set forth, and therefore it is taken as being illustrative, and not as limited. With this in mind, the invention has been illustrated in the accompanying drawings in which:—

Figure 1 is a perspective view showing the hat carried by the toy covering the opening in the table.

Figure 2 is a similar view but showing the hat elevated and one of the shelf-like segments on the wheel raised through the opening in the table.

Figure 3 is an approximately central vertical longitudinal sectional view through the

construction in the table, illustrated in Figure 1, a portion of the figure being also shown in section.

Figure 4 is a substantially similar sectional view taken through the construction as illustrated in Figure 2.

Figure 5 is a horizontal sectional view approximately on the line 5—5 of Figure 2.

Figure 6 is a sectional view approximately on the line 6—6 of Figure 5.

Figure 7 is a sectional view approximately on the line 7—7 of Figure 5.

Figure 8 is a sectional view approximately on the line 8—8 of Figure 7.

Figures 9 and 10 illustrate details.

Referring now to the drawings in detail, the numeral 1 designates the base plate of the improvement on which there is removably secured the flanged edges of a hollow member in the nature of a casing but which, in view of the nature of the improvement, I will hereinafter refer to as the table. The table is indicated by the numeral 2, and may have both its sides and ends at the upper portions thereof inclined inwardly toward the flat top 3. The top 3 is provided with a substantially rectangular opening 4. At the rear of the table there is secured on the base 1 a figure representing a magician and which is indicated by the numeral 5. The arms 6 of the figure are pivotally secured to the shoulders thereof, as indicated by the numeral 7, and the hands of the figure have pivotally supported thereto a hollow member which is elliptical in plan and which has its lower edge flanged, the said member representing a hat and is indicated in the drawings by the numeral 8. The flange or rim of the hat is designed to rest over the flat top 3 of the table 2, and the hat is of a size to fully cover the opening 4 in the top 3 of the said table.

On the base, approximately centrally with but slightly to the sides of the opening 4 in the top of the table there are hollow uprights 9 respectively. The tubular uprights have their confronting faces notched longitudinally from their outer ends for a desired distance, as indicated by the numeral 10 and likewise have their surfaces which confront the front and rear of the table provided with notches 11 and 12 respectively. In the tubular uprights 9 there are rods 13. The upper ends of these rods are formed with angle extensions 14, which pass through

65

90

95

100

105

110

the notches 10, the said rods having their lower ends arranged at an outward angle and projected through the notches 11. For distinction, the lower angle portions of the 5 rods are indicated by the numeral 15, the same having their extremities bifurcated. Pivoted in the bifurcated ends of the portions 15 of the rods 13 are levers 16 respectively. Each lever is pivoted on a support 10 17 that is secured to and arises from the base 1. The upper angle ends 14 of each of the rods 13 has secured thereon a laterally extending plate 18, and the said plates may be slightly rounded longitudinally, if desired. 15

Journalized in suitable bearings provided in uprights 19, and also in bearings provided by the uprights 9, if desired, there is a shaft 20. On the shaft 20 to one side of one of 20 the tubular uprights 9 there is a comparatively small star wheel 21. Keyed or otherwise secured on the shaft 20 between the tubular uprights 9 are hubs 22, from each of which radiates tubular 25 spokes 23 respectively. The spokes 23 are arranged in opposed pairs and are designed to receive therein fingers in the nature of rods 24 that have their outer ends connected to plates 25 which I shall hereinafter refer 30 to as shelves. Between the shelves 25 and the barrel 26 that connects the spaced hubs 23 there are spring means 27 connected to both the barrel and the respective shelves, the said spring means normally holding the 35 shelves 25 in contacting engagement with the outer ends of the spokes 23. One of the shelves 25 at all times rests on the plates 18 provided on the upper angle ends 14 of the rods 13. Each shelf is preferably 40 of a size greater than the area of the opening 4 in the top 3 of the table 2, but each shelf has arranged on the outer face thereof an angle tray 28, and in each of the trays there is removably secured the articles 29 45 to be displayed. It will be apparent that when the star wheel 21 is contacted, in a manner presently to be described, the shaft 20 and consequently the wheel will be rotated, and it will be further apparent 50 that when the levers 16 are contacted, also in a manner presently to be described, the rods 13 carrying the plates 18 will be elevated through the uprights or standards 9, the lever and the star wheel being alternately contacted so that when the 55 wheel is not rotated, the plates 18 on the rods 13 will elevate one of the shelves 25 through the opening 4 in the top of the table 2, the spring means between the shelf and the 60 barrel between the hubs of the wheel returning the said shelf to within the table immediately prior to the rotation of the wheel. In this manner it will be seen that the articles 29 upon the separate shelves will be 65 successively displayed on the top of the table.

During the time required in the lowering of the shelf, the turning of the wheel and the next successive contact of the levers to elevate the second shelf and tray, the table top is covered by the hat 8 of the figure 70 5, so that the movement of the shelf or wheel is not apparent to an observer.

On the base 1, to the rear of one of the uprights 9, and to one side thereof there are spaced upstanding arms 30 respectively, the 75 said arms being provided with bearing openings for a shaft 31. Keyed on this shaft there is a toothed wheel 32. The teeth of the wheel 32 are equal in number to the teeth of the star wheel 21, and the number of the teeth of the star wheel corresponds with the number of shelves carried by the wheel. The wheel 32 is of a materially greater size than the star wheel. Keyed on the shaft 32 there is a gear wheel 33, the latter being in mesh with a pinion 34 keyed on a shaft 35 arranged transversely of the base 1 and having its ends journalized in suitable bearing supports 36. The shaft 35, adjacent to its ends has secured thereon cam members 37, the said cams being in the path of contact with the levers 16 and are of a length not only to swing the levers to raise the rods 13 to operate the shelves as above described, but also to hold the shelves so raised for a period corresponding to the time required in the raising and lowering of the hat 9, and also corresponding with the period of time required between the contacting engagement of the teeth or fingers on the wheel 32 with 100 the teeth or fingers on the star wheel 21.

On the second end of the shaft 31 there is a comparatively large gear wheel 38 which is in mesh with a pinion 39 keyed or otherwise secured on a shaft 40 journaled in 105 bearings 41 supported from the base 1 and having its outer end provided with a wheel 42 which is preferably peripherally grooved for the reception of a belt, the said belt being driven by any suitable source of power 110 (not shown). It is, of course, to be understood that the shaft 40 may be hitched directly to a motor, if desired.

On the shaft 35, to one side of the cams 37 there are secured pairs of trip fingers 43 respectively. These fingers are in the path of contact with the levers 44, the said levers being pivotally supported on uprights 45 secured to the base 1. The levers have their ends nearest the figure 5 pivotally connected to the bifurcated ends 46 of rods 47. The opposite ends of the rods 47 are also bifurcated and are pivotally connected to lugs 48 on the shoulder portions of the arms 6 of the figure 5. It is, of course, to be understood that the figure is suitably clothed so that the body, arms, rods 47 and lugs 48 will be suitably concealed.

It is believed that the construction and operation of the improvement will be ap- 120 125 130

parent from the foregoing description when taken in connection with the drawings, but as previously stated it is to be understood that the showing is merely illustrative and is 5 susceptible to various changes and modifications. In the illustrative embodiment the improvement is designed as an advertising novelty for the show windows of jewelers, the trays on the shelves having supported 10 thereon different articles of jewelry, but it is apparent that other articles or objects may be arranged upon the separate trays. It will be further apparent that by a slight change in the construction, the figure may 15 manipulate two hats and the objects on the trays may represent animals, birds, etc.

Having described the invention, I claim:—

1. In an advertising novelty, a casing having an open top and representing a table, 20 a figure having movable arms positioned at one side of the table, a flanged casing representing a hat carried by the hands of the figure and normally over the opening in the table, revolute means in the table, articles 25 to be displayed carried thereby, means for imparting a continuous intermittent motion to the revolute means, means for singly projecting the articles therefrom through the opening in the table when the wheel is 30 halted, means for automatically returning the article to normal position when the wheel is in motion, and means for swinging the arms of the figure to bring the hat thereof away from the opening when an article is 35 in display position and for again swinging

the arms to bring the hat over the opening when the revolute means is actuated.

2. In an advertising novelty, a hollow casing representing a table having an opening in the top thereof, a figure at one side of the table, arms pivotally secured thereto, a flanged hollow member representing a hat pivotally secured to the hands of the arms of the figure and normally disposed over the opening in the table, a wheel revolvably mounted in the table having hollow spokes, shelves having fingers received in the spokes, spring means influencing the shelves to spoke contacting position, a tray on each shelf having an article to be displayed, means for imparting a continuous intermittent motion to the wheel to bring the trays directly below the opening in the table when the wheel is halted, means actuated by the means for rotating the wheel for elevating the shelf below the table opening to arrange the tray and article thereon through said opening when the wheel is halted, means also actuated by said operating means for swinging the arms of the figure to raise the hat when the article is in display position, means actuated by said operating means for lowering the shelf and tray prior to and at the time of the turning of the wheel and for also swinging the arms of the figure to bring the hat thereof over the opening in the table. 60

In testimony whereof I hereby affix my signature.

ERNEST THOMAS GARLICK.
